ART OF GRINDING

John E. Caster, Covington, Ky., assignor, by mesne assignments, to Cincinnati Grinders Incorporated, Cincinnati, Ohio, a corporation of Ohio

Original application April 14, 1926, Serial No. 102,067. Divided and this application December 12, 1930, Serial No. 501,915

5 Claims. (Cl. 51—278)

This invention relates to improvements in the art of grinding and especially to a novel process for the production of articles of circular form in cross section having a predetermined final axis.

5 This application is a division of an application filed April 14, 1926, for a Grinding machine, Serial Number 102,067 which issued on February 10, 1931 as Patent No. 1,791,442.

Prior to the present invention it has been customary to produce articles of this type on what is known as a center grinding machine in which the article is supported by the two rigidly fixed centers and the work and wheel given a relative feeding movement, one toward the other. With 15 articles of any appreciable length it has been customary to use a steady rest or member backing up the work to eliminate the variations due to spring of the work or yielding of the centers during the grinding. These operations, however, 20 have not been entirely satisfactory, particularly in the case of work which is initially out of round, or in which the centers are not concentrically located, due to the fact that during the grinding of such articles the grinding wheel would 25 strike the work only intermittently or with a chopping action and in addition, due to the fact that with such work it is impossible to so adjust the steady rest member as to continuously engage and support the work prior to the rounding 30 up thereof.

It is, therefore, one of the objects of the present invention to provide a novel method of producing work pieces of this character which shall make it possible to eliminate the individual dogging of the work pieces, by providing a different 35 manner of supporting said work pieces and effecting their rotation and in providing a backing member which shall positively engage the work during the entire rotation thereof, and itself produce the pressure of the work against the grinding 40 wheel, in place of depending upon the centers for applying the work pressure.

Another object of the present invention is the provision of an improved method of producing 45 work pieces in which the work is floated in the throat of a centerless grinder and the floating movement of the work in the direction of the grinding wheel limited while it is being rotated about a definite axis.

50 A further object of the invention is the provision of an improved process of concentric grinding of work pieces having a plurality of portions thereon to be finished or ground concentric with a predetermined axis utilizing a centerless grinder for the accomplishment of said process.

Other objects and advantages of the present invention should be readily apparent by reference to the following specification considered in conjunction with the accompanying drawings illustrating the several steps of the process and 60 the mode by which they are accomplished and it is to be understood that any modifications may be made in the exact order of the steps of the process, within the scope of the appended claims, without departing from or exceeding the spirit 65 of the invention.

In the drawings:

Figure 1 is a fragmentary end elevational view of a centerless grinder for accomplishing the process of this invention.

70 Figure 2 is a fragmentary plan view of a slightly modified form of apparatus for use in utilizing the process of this invention.

Figure 3 is a fragmentary view illustrating the progress of stock removal from the work 75 piece.

Figure 4 is a fragmentary view illustrating the general steps of the process.

Figure 5 is a diagrammatic view particularly illustrating the manner of limitation of size of 80 the work piece.

Figure 6 is a sectional view taken on line 6—6 of Figure 2.

In the drawings in which similar characters of reference are employed to denote corresponding 85 parts throughout the several views. A designates the bed of a grinding machine, having suitably journaled thereon the grinding wheel B operable at a high or grinding rate of speed and moving in a clockwise direction, as viewed in Figure 1, while opposing said wheel B is a regulating wheel C, supported on a slide D, for movement toward and away from the grinding wheel. This wheel is also driven in a clockwise direction at a slow rate of speed for regulating the rate of rotation of the work, the operative surfaces of the two 90 wheels, therefore, at their adjacent point moving in opposite directions. Rising from the bed intermediate these wheels is the bracket E, supporting the angle top work rest 10. This bracket, as shown in Figure 2, also supports the floating headstock spindle 11, having a ball end 12 swiveled in socket 13 of adjustable slide block 14. This block is movable in a bore 15 of bracket 16, being locked against rotation by a screw 17 engaged in the keyway 18 and being inwardly adjustable by screw 19. A pin 20 projecting from the sides of ball end, riding in elongated slots 20' of the block 14, prevents rotation of spindle 11 but permits a free action of ball socket.

100

105

110

To control the position of this spindle a second or supplemental bracket portion 21 is provided having a passage 22 of a size to receive the inner end of the spindle 11, with suitable clearance permitting limited universal oscillatory movement of the spindle. This bracket is further provided with a spring device 23 bearing against the end of the spindle to prevent the regulating wheel from lifting the work from the blade when the grinding wheel is not in contact with the work.

It is to be noted that the parts just described are on opposite sides of the grinding throat, as viewed in Figure 2.

One particularly desirable use for a machine of this character is in the concentric production of a second cylindrical face on a two diameter work piece, as for example, the work piece illustrated in Figure 2 of the drawings, having the larger diameter portion 27, which has been ground in a prior operation concentric with its centers by either center or centerless methods and having a second portion 28 which must be formed concentric or co-axial with the portion 27. In the grinding of such work pieces, there is provided a work rest portion 29 on bracket E to engage the portion 27 and properly support it in the machine when the portion 28 is resting on the upper surface of the work rest 10. It is to be understood that the work piece 27-28 is provided with the customary centers adapted to receive the points of the head and tailstock spindles 11, that one placed at the forward side of the machine or to the left as viewed in Figure 2, is then brought in through the medium of hand wheel and screw 19', and the height of the work rest and supporting block are such that the points of the spindles will automatically engage the centers, slightly backing up or raising the piece but not sufficiently to destroy contact between the members 10 and 28.

In grinding of work by the centerless method, the work piece is supported on a work rest between grinding and regulating wheels and is allowed to find or establish its own center, the diameter being determined by the final separation between grinding and regulating wheels. In work of the present nature, however, it is necessary that the axis of the work be determined by the position of the centers in its two ends. At the same time, it is desirable that the grinding operation be as continuous as possible and the work satisfactorily backed up during the entire grinding operation. This presents a number of difficulties or problems which have for the first time been solved by the present machine. The machine, it will be noted, has two floating centers but one of them may be a fixed center and the other floating without limiting the beneficial results obtained from the machine. In any event, it is necessary with a floating center that some means be provided for limiting the final approach of the axis of the work to the grinding wheel, thus limiting the final size of the work and insuring the work in cross section being a circle whose center lies on the previously established axis. In the accomplishment of this result, use is made of a suitable stop for the oscillating spindle, this being shown in Figures 2 and 3, for example, as produced by forming a flat 30 on the spindle for engagement by the end of the micrometer adjusting screw 31, provided with graduations 32, coupled with the index finger 33 to show the amount of adjustment. Attention is particularly invited to the fact that this flat is not formed at right angles to the common axial plane of the grinding and regulating wheels, but on the contrary is formed

at an angle convergent to the operative face of the grinding wheel adjacent thereto. This angle is preferably substantially parallel to a tangent to the regulating wheel at the point of contact with a finished work piece.

The action of the machine and the reason for this particular relationship of the parts will probably be best understood by reference to Figures 3, 4 and 5. Figure 3 illustrates the actual operation of the machine in rounding up a work piece which was initially eccentric to the predetermined axis. M indicates the original exterior of the work piece shown as substantially a true circle, but true as respects the center or axial line N and eccentric as respects the axial line O, which is determined by the position at which the two centers are placed in the ends of the work and about which, therefore, final work piece curve must be generated. The grinding is considered as starting at the point P, being produced by an inward feeding movement of the regulating wheel C pressing the work against the grinding wheel. Q indicates the final size of the work desired, being a circle generated about the point O as a center. It is, of course, to be understood that the dimensions here shown are greatly exaggerated to facilitate an understanding of the invention, as in actual practice the total of stock removal would probably not exceed .050". As the grinding starts at P and the grinding wheel C is given a uniform inward movement by suitable manual or automatic mechanism, the original grinding will be in the form of a uniform spiral path R. This grinding will continue and the shifting supporting center or centers will move with the work toward the grinding wheel until stop screw 31 engages the flat 30 on said spindle. This limits the further movement of the spindle toward the grinding wheel and consequently limits the amount of stock which the grinding wheel can remove. The point at which this limitation occurs has been indicated as S. As the regulating wheel continues to rotate the work and move inwardly a different spiral of stock removal will be produced. As S is practically zero the stock removal at a diametrically opposite point or T, will be substantially double that of the initial spiral considering a constant movement of the regulating wheel. This movement will continue in successive displaced spirals, as indicated, until the regulating wheel reaches its innermost position of movement determining the final size of work piece when the spirals will have merged into the final outline Q.

This limiting effect will probably be better appreciated by reference to Figure 5, in which the stop, regulating wheel and work rest are diagrammatically indicated as being the three points determining the final size and position of the work piece; the point U being shown where the tangent to the regulating wheel at the point of contact with the final work piece is also tangent to the surface of the work; the point W being the point of contact of the surface of the work with the supporting work rest and the point X being the point determined by engagement of the flat on the supporting spindle with the stop, which may be considered as a concentric circle of the work piece, as indicated by the dotted line circle Y. The effect is the same as though this were a second tangent or contacting member operating on the final size of the work corresponding to the dotted tangent X' parallel with the flat 30 of the headstock spindle. It will thus be seen that the three contacting members indicated in the dia-

gram by U, X and W form a three point bearing, determining the position of the finished work piece while the grinding wheel is a fourth member, the other members being so adjusted relative 5 to the grinding wheel that the grinding wheel will produce the desired circular outline Q removing all points on the surface of the work exterior to circle Q when the final position is determined as noted by being prevented by the 10 three determinants from cutting into the work within said desired circle.

It will be understood by those conversant with the general grinding operations that after a work piece has been reduced to size and brought up 15 against a stop, if the grinding wheel and work piece both continue to rotate for an appreciable period, there is a certain spring in the parts and general yieldability tending to produce a 20 sparking out or final grinding and at the same time, if relative rotation of the parts continues, to cause a cutting below the exact predetermined size as established by the stop. This must be given particular consideration in connection 25 with the present mechanism in which a considerable amount of grinding has to be done on one side of the piece, while very little grinding takes place on the opposite side. The present mechanism has, therefore, been designed to particularly take care of this point. In the centerless grinding operation of the work receiving 30 throat for practical purposes may be considered as V shaped, that is to say the grinding is done above the axial plane connecting the grinding and regulating wheels, with the result that the 35 wheels converge below the work and as the size of the work decreases, it tends to drop down into this throat as is indicated by the centers Z, Z' and Z'', as shown in Figure 4. This dropping of the center would, therefore, tend to allow a 40 slight stock removal if the stop were operated in a vertical plane. To accentuate this, however, and at the same time to permit of desired upward yielding movement of the parts and prevent clamping or wedging between the stop and 45 regulating wheel, the surface 30, as has been previously mentioned, is disposed at an angle converging toward or approaching the grinding wheel surface so that there is both inward and downward movement as the diameter of the work 50 decreases. In this manner it is possible for the stop to come into operation as indicated in Figure 5, limiting grinding action on the side of shorter radius and then the combined action of downward dropping and inward sliding which produces, in other words, the effect of a receding stop 55 device, allowing limited amounts of material to be removed on the shorter radius for each maximum amount removed on the longer radius. As a result the surface of the shorter radius each 60 time receives a slight but proper amount of grinding action, preventing the formation of flats or indentations therein by the grinding wheel and insuring a more steady and uniform rotation of the work piece, due to the fact that there 65 is thus maintained a constant pressure between the work piece, regulating wheel and grinding wheel, until the work has been reduced to its final finished form. This eliminates the irregular action of the grinding wheel which is characteristic of truing up work of this nature in 70 the standard center grinding machines.

Of course, the same result here described could be attained by the use of a substantially straight stop member together with means for causing it 75 to variably recede during the grinding operation

as is brought out, for example, in Figure 1. In this figure there is shown a rock lever 34 pivoted to the bracket E and coupled with the regulating wheel slide D by a link 35, being so proportioned that the stop will move back a limited amount in proportion to the inward movement of the regulating wheel.

While the foregoing invention has been particularly illustrated and described as utilizing what is termed a centerless grinder, which is to say a grinder having a pair of opposed wheels and an intermediate work rest, it is to be understood that the broad principles of grinding here illustrated are capable of adaptation to center type grinders or the like in which a floating center is employed in combination with means for limiting its movement in the direction of the grinding wheel and in which suitable means are employed for urging and holding the work piece in contact with the grinding wheel.

What is claimed is:

1. The process of producing a work piece of circular form in cross-section with a predetermined axis in a centerless grinder, consisting in forming centers to establish the axis of the work piece, introducing the work piece between the grinding and regulating wheels of a centerless grinder, supporting the work piece peripherally in said grinding throat for free movement relative to the wheels, as imparted by the support, decreasing the width of the grinding throat to cause the desired stock reduction and limiting the movement of the centers and established axis in the direction of the grinding wheel.

2. The process of producing a work piece of circular form in cross-section with a predetermined axis in a centerless grinder, consisting in forming centers to establish the axis of the work piece, introducing the work piece between the grinding and regulating wheels of a centerless grinder, supporting the work piece peripherally in said grinding throat for free movement relative to the wheels, as imparted by the support, decreasing the width of the grinding throat to cause the desired stock reduction and limiting the movement of the centers and established axis in the direction of the grinding wheel and producing a relative receding action of the limiting mechanism, as the work piece approaches size whereby formation of flats is prevented.

3. The process of producing an article of circular form in cross-section with an axis other than its original axis of mass, consisting in supporting the article for floating movement between grinding and backing members, spirally removing the surface of the article whereby a given reduction in diameter is effected for each revolution of the work, limiting the approach of the established axis in the direction of the grinding wheel to cause the greater amount of stock reduction to take place on the longer radius of the work and producing a receding action of the limiting mechanism during grinding whereby continuous grinding is performed on all portions of the surface of the work until the same is reduced to final circular form about the predetermined axis.

4. The process of producing an article of circular form in cross-section with a given axis of generation for the peripheral surface thereof, consisting in holding the article against an abrading wheel for continuous operation of the wheel on the surface thereof, and controlling the amount of stock removed from different arcs of said surface during each rotation, whereby the greater

amount of stock is removed on the longer axis at each of said rotations to reduce the piece to final form by continuous grinding of variable amounts from the several points on the periphery thereof.

5. The process of producing a work piece having a final surface concentric with a predetermined axis consisting in initially determining the desired axis therefor, mounting the work piece in the throat between the grinding and

regulating wheels of a centerless grinder, peripherally supporting the work for free floating movement transversely of the throat and laterally with respect to the throat, and positively limiting the amount of movement of the predetermined axis in the direction of the point of engagement between the work and grinding wheel whereby the final work piece surface will be produced concentric with said preestablished axis.
